(57) **CLAIM**

The ornamental design for a child's activity toy, as shown and described.

DESCRIPTION

FIG. 1 is a front, right side, top perspective view of a child's activity toy, showing my design.

FIG. 2 is a rear, left side, bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The grayscale tones shown in the drawing figures are intended to illustrate color contrast, and not any particular shade or tone of color.
